UNITED STATES PATENT OFFICE.

ABBE SPRUNG, OF NEW YORK, N. Y.

ADJUSTABLE SECTIONAL FURNITURE.

1,247,590.

Specification of Letters Patent. Patented Nov. 20, 1917.

Application filed April 1, 1915. Serial No. 18,439.

To all whom it may concern:

Be it known that I, ABBE SPRUNG, a citizen of the United States, and a resident of New York, in the county of New York and 5 State of New York, have invented certain new and useful Improvements in Adjustable Sectional Furniture, of which the following is a specification.

This invention relates to improvements in 10 furniture of the cabinet, table or desk type, in which one portion is movable with relation to another.

The objects are first, to provide mechanism for manually operating such movable portion with very little effort, a countervailing device, having an adjustable tension being combined in the mechanism.

Second, to rigidly lock the movable portion at any predetermined position desired, 20 with respect to the main portion, the operating and locking means being controlled by a single handle convenient to the operator.

Third, to provide an improved form of 25 guides for the movable portion capable of holding it in lateral and longitudinal control irrespective of limited variations in the parts caused by expansion or contraction, shrinkage and the like, which would ordinarily cause difficulty by binding or slackening of adjacent portions.

These and other objects, such as economical construction, neatness in appearance and simplicity, are attained by the novel construction and combination of parts herein- 35 after described and shown in the accompanying drawings, forming part of this specification, and in which:—

Figure 1 is a general perspective view of 40 a flat top desk made in accordance with the invention, the movable portions being shown in an elevated position by broken lines.

Fig. 2 is a partial plan view of the same, parts being broken away in order to see the construction.

Fig. 3 is a sectional view taken on line 45 corresponding to 3—3 of Fig. 2.

Fig. 4 is a plan view of the handle.

Fig. 5 is a side view of the same.

Fig. 6 is a perspective view of the end 50 guides partially extended, and,

Fig. 7 is a similar view of the same but showing the guides in a closed position.

The mechanism involved in this invention may be appropriately used in connection 55 with various forms of furniture, such as tables, wardrobes, dressers, sewing machine

stands, work benches, tool cabinets, business files and many others.

In this case a desk has been used as an illustration, the pedestals 10 of which may 60 be filled with drawers 11 as is customary and the top, in place of being one unbroken surface, is made in sections, one, the front 12, being rigid with the pedestals and the other 13, at the rear, normally covering over an 65 opening in the back of the desk, may have an extension provided with pigeon-holes, drawers, etc., as preferred. This section is arranged slidably within the opening and can rise therein to some distance above the 70 level top.

The lower element 14, of this movable section, has secured longitudinally to it an angle 75 15 for the purpose of giving it rigidity and to the angle are attached two small brackets 17, each having links 18 pivotally connected at their lower ends with one arm of the levers 19, which are fulcrumed on a shaft 20, and rigidly secured thereon.

This shaft is rotatably mounted in brackets 80 22 fastened to a bar 23, or other equivalent support forming part of the furniture structure.

To another arm 24, of one of the levers 19, is attached a link 25 engaging with one 85 arm 27 of the bell crank lever 28, which is pivotally mounted on a bracket 29 attached, in the present case, to one of the pedestals 10 in such manner as to extend laterally into the knee space.

The outer end of the bell-crank lever 28 is fitted to be received in the operating handle 30, which is limitedly slidable thereon and held in engagement by means of the pin 31 which passes through the inner end 95 of the handle and the slot 32 formed in the lever, the coiled push spring 33 keeping the handle in a normally extended position.

In order to adjust the height of the sliding member 13, through the described mechanism the pin 31 is suited to be received in any of the openings 34 formed in the arcuate keeper 35 secured, like the bracket 29, to one of the pedestals 10; thus it will be seen that by pressing the handle 30 inwardly 100 against the thrust of the spring 33, the pin 31 is disengaged from the keeper 35 and the handle operated by raising or lowering it thereby effecting changes in the position of the section 13.

To enable an operator to accomplish this 110 with the least effort use is made of springs

38, coiled about the shaft 20, one end of the 5 springs being secured to the brackets 22, the other fastened to the collar ratchet 39 loosely mounted on the shaft 20 and provided with teeth engaging with a collar 40 having lateral teeth and pinned or otherwise held rigid with the shaft; obviously the tension or torque of the spring may be varied at will so as to wholly or in part 10 counterbalance the weight of the movable section 13 together with whatever contents it may contain.

The sliding section is provided with metal guides 42 at each end, the same being rigidly 15 attached and operable slidably in connection with an intermediate guide member 43, the latter in turn being controlled by another guide member 44 secured within the opening of the desk; these guides are preferably 20 semi-circular in cross section and so nested as to operate telescopically, affording an effective means for causing the movable section to operate vertically and preventing it from lateral or longitudinal displacement.

25 It is known that desks having a "disappearing" section exist, but because of the expense in construction, the difficulty of operation and general unsightliness they are not in common use; therefor I do not 30 broadly claim the same but it is believed that the simplicity of parts herein indicated, and ease of operation obtained by them, is new and constitute improvements; having thus described the invention and pointed out 35 the manner in which it is constructed, applied and used, what I claim as new and desire to secure by Letters Patent, is:—

1. An article of furniture having a sectional wall of which one member is movable 40 in a direction perpendicular to and into and out of the plane of the other member and which carries a compartmental case, extension guides disposed parallel with the path of movement of said movable wall 45 member and connecting the same with the body of the article of furniture, said guides

50 consisting of telescoping transversely arched members provided with means for limiting their relative movements, and means for operating the movable member.

2. An article of furniture having a sectional wall of which one member is movable in a direction perpendicular to and into and out of the plane of the other member and which carries a compartmental case, extension guides disposed parallel with the path of movement of said movable wall member and connecting the same with the body of the article of furniture, said guides 55 consisting of telescoping transversely arched members provided with means for limiting their relative movements, and means for operating the movable member including a bell crank lever having a link connection with said member and disposed to operate in a 60 plane between those of said extension guides.

3. An article of furniture having a sectional wall of which one member is movable in a direction perpendicular to and into and out of the plane of said wall, said movable 70 member carrying on its inner face a compartmental case, extension guides for determining the path of said movable member, means for operating said movable wall member and consisting of a bell crank lever having a link connection with the movable member, the power arm thereof being long 75 relatively to the operating arm, and a hand lever of bell crank type connected with the operating arm of the first named lever, and means for locking said hand lever in its adjusted positions, said means including a segment having seats and the movable grip having a latch for engagement with said seats.

80 In testimony whereof I have signed my name to this specification in the presence of two subscribing witnesses.

ABBE SPRUNG.
